UNITED STATES PATENT OFFICE.

LOUIS IANNELLE, OF NEWTON, MASSACHUSETTS.

FASTENING DEVICE FOR DETACHABLE SHOE HEELS.

Application filed August 8, 1921. Serial No. 490,449.

To all whom it may concern:

Be it known that I, LOUIS IANNELLE, a subject of the King of Italy, residing at Newton, in the county of Middlesex and 5 State of Massachusetts, have invented new and useful Improvements in Fastening Devices for Detachable Shoe Heels, of which the following is a specification.

This invention relates to a fastening device for a detachable shoe heel.

The object of the invention is to so construct a heel for boots and shoes that a portion of said heel, preferably constructed of rubber, may be easily and quickly detached 15 from the permanent portion of said heel in order that said detachable portion may be replaced when worn without the use of nails and tools.

Still another object of the invention is to 20 provide a novel means for preventing the detachable heel from rotating upon the permanent portion of the heel.

The invention consists in the combination and arrangement of parts set forth in the 25 following specification and particularly pointed out in the claims thereof.

Referring to the drawings:

Figure 1 represents a longitudinal section through the heel portion of a shoe, the heel 30 embodying my invention being illustrated attached thereto.

Fig. 2 is a perspective view of the spring clip.

Like numerals refer to like parts throughout the several views of the drawings.

In the drawings, 5 represents a portion of the upper of a shoe, 6 the sole and 7 the heel seat. Secured to the heel seat 7 in any suitable manner as, for example, by nails 8 40 is a lift 9 preferably constructed of leather. A metal plate 10 is secured to the under surface of the lift 9 by means of nails 11. Formed integral with the plate 10 is a downwardly projecting member 12 which is 45 approximately conical in form and is provided with a spirally arranged screw-thread 13 extending therearound, said screw-thread increasing in diameter from the lower end of said member upwards.

50 A lift 14 preferably constructed of resilient material as, for example, rubber or a material embodying the properties of rubber, is secured to the lift 9 by means of the member 12. The upper surface of the lift 14 is 55 concaved at 15 in order that the upper edge of the lift 14 may closely fit the lift 9 when

the lift 14 is attached thereto. The lift 14 is provided with a recess 16 in the upper surface thereof, said recess being approximately conical in form and having a spirally arranged screw-thread 17 extending therearound which is adapted to fit and interlock with a screw-thread 13 upon the member 12. The pitch of the screw-thread is such that one half a turn of the lift 14 upon the member 12 is sufficient to securely interlock said lift 14 with the member 12 and draw the curved surface 15 tightly into contact with the under-surface of the lift 9.

When in position the lift 14 is prevented from rotating upon the member 12 by means of a spring clip 18. The clip 18 is embedded in the lift 14 and is provided with longitudinally extending grooves upon the outer surface thereof which prevent the clip from 70 rotating within the lift 14. The clip is furthermore provided with an interiorly screw-threaded portion 20 which prevents the clip from being pulled outwardly from the lift 14. The clip 18 is also provided with 75 a plurality of longitudinally extending slots 21 which form resilient fingers 22 adapted to be sprung into engagement with a projection 23 formed integral with the metal plate 10. A shallow recess 24 is provided 80 upon the inner surface of the fingers 22 and when the lift 14 is in position, a projection 23 which is partly spherical in form is located in the recess 24.

In attaching the detachable lift 14 to the 90 permanent lift 9 the lift 14 is held with the front edge thereof facing toward the rear of the shoe and then brought into engagement with the metal member 12, each thread of the lift 14 engaging the corresponding 95 thread of the member 12. The lift 14 is then given one-half a turn which is sufficient to tightly interlock each succeeding thread and draw the curved surface 15 of the detachable lift 14 into engagement with the undersurface of the permanent lift 9. During this 100 operation the front portion of the lift 14 is sprung downwardly to avoid the projection 23, but when the lift 14 has been rotated to a position where the spring clip 18 is in 105 alignment with the projection 23, the front portion of the lift 14 is released and the spring clip 18 is sprung into engagement with the projection 23. The lift 14 is now securely fastened to the lift 9 and cannot be 110 accidentally rotated upon said lift.

When it is desired to replace a worn lift

14 with a new lift, it is simply necessary to force the forward portion of the lift 14 downwardly to disengage the spring clip 18 from the projection 23 and then rotate the lift 14 one-half a turn in the proper direction to disengage said lift from the member 12.

The great advantage derived in constructing a heel as illustrated is that it allows all 10 of the screw-threads to interlock with only one-half of a turn of the detachable lift, and no cement or nails are necessary in securing the detachable lift to the permanent lift and no tools are required in either applying or detaching the detachable lift.

It is evident that the permanent lift 9 may be eliminated if it is so desired and the lift 14 attached directly to the heel seat 7 without departing from the spirit of this 20 invention. At this time the plate 10 is nailed directly to the heel seat and the detachable lift 14 is attached to the member 12 in the same manner as previously described. The detachable lift in such cases, aside from being 25 slightly increased in thickness, is identical with the detachable lift 14 previously described.

I claim:

1. In combination, a plate provided with

a projection formed integral therewith, and 30 a spring clip embodying therein a plurality of resilient fingers adapted to spring into engagement with said projection upon said plate, said clip being provided with a plurality of longitudinally extending 35 grooves upon the outer surface thereof, said clip also being provided with a plurality of screw-threads upon the interior thereof.

2. In combination, a member, a spring clip embodying therein a plurality of resilient fingers, said clip being provided with a plurality of longitudinally extending grooves upon the outer surface thereof adapted to co-operate with the material of 40 said member to prevent the rotation of said clip therein, said clip also being provided with a plurality of screw-threads upon the interior thereof adapted to co-operate with the material of said member to prevent a longitudinal movement of said clip within 45 said heel.

In testimony whereof I have hereunto set my hand in presence of two subscribing witnesses.

LOUIS IANNELLE.
